FIG. 5.

Des. 190,838

PAGE 5

FIG. 6.

FIG. 7

FIG. 1 is a top plan view of a Hair Dryer Power Unit or similar article, showing our new design;

FIG. 2 is a rear elevational view thereof;

FIG. 3 is a front elevational view thereof;

FIG. 4 is a bottom plan view thereof;

FIG. 5 is an end elevational view thereof;

FIG. 6 is a bottom perspective view, the hose connector being omitted for convenience in illustration; and

FIG. 7 is a top perspective view thereof, the lever

handle and hose connector being omitted for convenience in illustration.

We claim:

The ornamental design for a hair dryer power unit or similar article, substantially as shown and described.
